(57) CLAIM

The ornamental design for a sink cover set, as shown and described.

DESCRIPTION

FIG. 1 is a top perspective view of a sink cover set set, showing my new design;

FIG. 2 is a bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a top perspective view of the sink cover set in a detached state;

FIG. 10 is a top perspective view of the first piece of a sink cover set, showing my new design;

FIG. 11 is a bottom perspective view thereof;

FIG. 12 is a front elevational view thereof;

FIG. 13 is a rear elevational view thereof;

FIG. 14 is a left side view thereof;

FIG. 15 is a right side view thereof;

FIG. 16 is a top plan view thereof;

FIG. 17 is a bottom plan view thereof;

FIG. 18 is a top perspective view of the second piece of a sink cover set, showing my new design;

FIG. 19 is a bottom perspective view thereof;

FIG. 20 is a front elevational view thereof;

FIG. 21 is a rear elevational view thereof;

FIG. 22 is a left side view thereof;

FIG. 23 is a right side view thereof;

FIG. 24 is a top plan view thereof;

FIG. 25 is a bottom plan view thereof;

FIG. 26 is an enlarged view of detail 26 in FIG. 2;

FIG. 27 is an enlarged view of detail 27 in FIG. 2;

FIG. 28 is an enlarged view of detail 28 in FIG. 3;

FIG. 29 is an enlarged view of detail 29 in FIG. 7; and,

FIG. 30 is an enlarged view of detail 30 in FIG. 8.

The dashed broken lines in the figures are for the purposes of illustrating portions of the sink cover set that form no part of the claimed design.

The dash-dot-dash broken lines are for notating enlarged views, which form no part of the claimed design.
